US0D1033505S

(12) **United States Design Patent** (10) **Patent No.:** **US D1,033,505 S**
(45) **Date of Patent:** **** Jul. 2, 2024**

(54) **VIDEO CAMERA**

(71) Applicants: **Chao Qin**, Hangzhou Zhejiang (CN);
Davy Ying, Hangzhou Zhejiang (CN)

(72) Inventors: **Chao Qin**, Hangzhou Zhejiang (CN);
Davy Ying, Hangzhou Zhejiang (CN)

(**) Term: **15 Years**

(21) Appl. No.: **29/816,859**

(22) Filed: **Nov. 25, 2021**

(30) **Foreign Application Priority Data**

Aug. 5, 2021 (CN) 202130504380.3

(51) **LOC (14) Cl.** **16-01**

(52) **U.S. Cl.**

USPC **D16/202**

(58) **Field of Classification Search**

USPC D16/200-203, 207, 209, 214, 217, 219;

(57) **CLAIM**

The ornamental design for a video camera, as shown and described.

DESCRIPTION

FIG. 1 is a front perspective view of a video camera showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings are for the purpose of illustrating portions of the video camera that form no part of the claimed design.

1 Claim, 7 Drawing Sheets
